UNITED STATES PATENT OFFICE

DANIEL R. COX AND DAVID A. KINNIE, OF PASADENA, CALIFORNIA.

MANIFOLD LOCK.

Application filed April 24, 1924. Serial No. 708,654.

To all whom it may concern:

Be it known that we, DANIEL R. COX and DAVID A. KINNIE, citizens of the United States, residing at Pasadena, in the county of Los Angeles and State of California, have invented new and useful Improvements in Manifold Locks, of which the following is a specification.

This invention is a manifold lock, and 10 consists of the novel features herein shown, described and claimed.

An object is to place a valve in the gas line from a carburetor to a manifold and extend the stem of the valve to the instrument 15 board and place a lock in the instrument board for operating the valve.

Other objects and advantages will appear from the drawings and specification.

The view illustrates the invention and 20 shows the construction partly in elevation and partly in section, the carburetor and manifold being broken away to economize space.

The details of the manifold lock shown in 25 the drawing are as follows:

The intake manifold 1 has a flange coupling member 2, which ordinarily fits against the flange coupling member 3 of the carburetor 4.

In applying our invention the valve casing 30 5 has a flange coupling member 6 fitting the coupling member 2 and a flange coupling member 7 fitting the coupling member 3, so that when the bolts 8 are applied the valve casing 5 is rigidly mounted in the gas line and has a passage 9 through which the gas passes from the carburetor 4 to the intake manifold 1. The valve casing 5 has a valve 35 seat 10 bored from the upper side of the casing crosswise of the passage 9. The valve member 11 fits rotatably in the valve seat 10 and has a large transverse bore 12 so that when the bore 12 is in line with the passage 9 the flow of gas is not interrupted and so 40 that when the valve member 11 is turned to bring the bore 12 crosswise of the passage 9, the gas line is effectively closed.

Port 13 leads downwardly from the top of the valve member 11 to the bore 12. An 45 interiorally screw threaded housing 14 is formed integral with the valve casing 5 and extends upwardly, the passage through the housing being larger than the valve member 11, so that the valve member 11 is inserted 55 downwardly through the housing 14

into the seat 10. A stem 15 extends upwardly from the valve member 11, a reducer 16 is screwed into the housing 14, and a cap 17 is screwed upon the small end of the reducer. 60

A flexible shaft construction 18 shown as a coil spring is connected to the upper end of the stem 15, a flexible shell 19 is connected to the reducer 17, and the flexible shaft 18 extends through the shell 19. The reducer 16 may be welded, soldered or brazed to the housing 14, as indicated at 20, and in a like manner the cap 17 may be welded, soldered or brazed to the reducer 16, as indicated at 21, so that the parts cannot be 70 easily disconnected.

A lock casing 22 is mounted through the instrument board 23 and dash 24, and the upper end of the flexible shell 19 is connected to the casing 22 by welding, brazing 75 or soldering, 25. The key lock 26 is mounted in the casing 22. A stem 27 extends from the rotating cylinder of the key lock and is attached to the flexible shaft 18, so that when the key lock 26 is properly operated and the key removed, the valve member 11 is crosswise of the gas passage and the intake manifold 1 is locked against receiving gas to operate the engine, and so that when the key 80 28 is inserted into the lock and properly operated the valve member 11 is turned to bring the bore 12 into the gas line and the manifold is unlocked and the engine may be operated. 85

In case a thief or other unauthorized person was to break the shell 19 and rotate the valve member 11 to open the gas line, the port 13 would furnish a surplus of air and prevent the engine from being successfully operated. 90

Normally the flexible shaft construction and key lock construction are closed to air so that the ports 13 serve no purpose until the flexible shaft construction is broken to admit air. 95

Thus, we have produced a manifold lock comprising a valve adapted to be introduced between a carburetor and an intake manifold and adapted to open and close the gas passage, and an enclosed flexible shaft construction extending from the valve and adapted to be connected to a key lock construction which may be mounted in any convenient position as upon a dash or instrument board. 100

Various changes may be made without departing from the spirit of our invention as claimed.

We claim:

5. 1. A manifold lock comprising a valve adapted to be introduced between a carburetor and an intake manifold and adapted to open and close the gas passage, a gas tight tubular shell leading from the valve, a shaft 10 leading through the tubular shell to turn the valve, and a port from the valve to the tubular shell.
15. 2. A manifold lock comprising a valve adapted to be introduced between a carburetor and an intake manifold and adapted to open and close the gas passage, a gas tight tubular shell leading from the valve, a shaft leading through the tubular shell to turn the valve, a lock connected to the shaft, and 20 a port leading through the valve from the gas passage to the tubular shell.
25. 3. A manifold lock comprising a valve adapted to be introduced between a carburetor and an intake manifold and adapted to open and close the gas passage, and an enclosed flexible shaft construction extending from the valve and adapted to be connected to a key lock construction which may be mounted in any convenient position as

upon a dash or instrument board, the valve member having lateral ports leading from the flexible shaft construction to the gas passage through the valve member.

4. A manifold lock comprising a valve construction adapted to be incorporated into a gas line, a flexible shaft construction leading from the valve construction, and a key lock construction at the outer end of the flexible shaft construction, there being ports which will be opened if the flexible shaft 40 construction is broken.

5. The combination with an intake manifold, a carburetor and an instrument board or dash, of a valve construction adapted to be inserted between the carburetor and the intake manifold, a flexible shaft construction leading from the valve construction and a key lock construction mounted through the instrument board or dash and connected to the flexible shaft construction, there being 50 ports through the valve construction which are normally maintained closed, and which are open when the flexible shaft construction is broken.

In testimony whereof we have signed our 55 names to this specification.

DANIEL R. COX.
DAVID A. KINNIE.
